COMBINED LAPEL BROOCH AND FLASHLIGHT

Albert Gelardin, New York, N.Y.

Application February 3, 1959, Serial No. 54,439

Term of patent 3½ years

(Cl. D45—19)

FIG. 1

FIG. 2

FIG. 3

FIG. 4

Fig. 1 is a front elevational view showing my design of a combined lapel brooch and flashlight.

Fig. 2 is a side elevational view.

Fig. 3 is a rear elevational view.

Fig. 4 is a bottom plan view.

I claim:

The ornamental design for a combined lapel brooch and flashlight, substantially as shown.
